EXERCISING DEVICE

William H. Maxwell, Newport Beach, Calif.

Application September 2, 1941, Serial No. 409,222

14 Claims. (Cl. 272—83)

This invention relates to exercising devices and it is a general object of the invention to provide a practical, effective and inexpensive device for exercising various muscles of the body, particularly those of the chest, back, shoulders and arms.

Another object of this invention is to provide an exercising device useful in correcting round shoulders and in developing and working the chest, back, neck and shoulder muscles.

Another object of this invention is to provide an exercising device of the character referred to that may be safely and effectively employed by persons of both sexes and of all ages without special skill or training.

Another object of this invention is to provide an exercising device of the character referred to the action of which may be varied to suit various individuals and for progressive corrective action and muscle development.

Another object of this invention is to provide an exercising device embodying a pair of swingable rods or bars to be grasped when the arms of the user are extended from his sides and having means for resisting inward swinging of the bars so that the user actively employs the muscles of his back, shoulders and neck when he draws the bars inwardly.

Another object of this invention is to provide an exercising device of the character mentioned in which the means for yieldingly resisting inward swinging of the bars are individually adjustable to provide the selected or required resistance at the respective bars.

Another object of this invention is to provide an exercising device of the character mentioned in which the bars are mounted to swing on both vertical and horizontal axes to provide for a wide range of operating conditions and to permit the bars to hang vertically adjacent the wall or other support when not in use.

Another object of this invention is to provide an exercising device of the character referred to having means for preventing downward swinging of the bars to retain the bars in position for immediate use and to relieve the user of the weight of the bars when this is desired or necessary.

Another object of this invention is to provide an exercising device of the character referred to embodying optional weight means for installation on the bars to apply additional weight to the user's arms, which weight means are adjustable along the bars to vary the extent of this additional load on the user.

Another object of this invention is to provide an exercising device of the character referred to embodying means for yieldingly resisting outward swinging of the bars or movement of the bars away from one another, which means is adjustable or capable of regulation to vary its action.

Another object of this invention is to provide an exercising device of the character referred to 10 embodying simple, dependable and very effective means for removably mounting the device on a wall or other support. A simple bracket or socket plate is provided on the wall to removably receive the body of the device, serving to dependably retain the device itself without the necessity of using screws, bolts or like means. The mounting plate may be readily mounted at the selected or required height and, if desired, vertically spaced mounting plates may be employed to provide for the positioning of the device at different elevations for use by persons of different heights.

Another object of this invention is to provide an exercising device of the character referred to 25 in which the means for yieldingly resisting inward swinging of each bar is individually adjustable by merely rotating the bar.

Another object of this invention is to provide an exercising device of the general character 30 mentioned which is extremely simple and inexpensive to manufacture, light in weight, convenient to handle and use, and also strong and durable.

A further object of this invention is to provide an exercising device of the character referred to 35 embodying novel and particularly effective means for supporting the bars for independent swinging and for rotation about their longitudinal axes.

The various objects and features of my invention will be fully understood from the following 40 detailed description of typical preferred forms and applications of my invention, throughout which description reference is made to the accompanying drawings, in which:

Fig. 1 is a front view of the device provided by this invention with the bars in depending positions and with weights applied to the bars. Fig. 2 is a side elevation of the device as shown in 45 Fig. 1. Fig. 3 is a top or plan view of the device as shown in Fig. 1. Fig. 4 is an enlarged fragmentary vertical detailed sectional view of one of the bar mounting means. Fig. 5 is a horizontal detailed sectional view taken as indicated by line 5—5 on Fig. 2, illustrating one of the weights.

Fig. 6 is an enlarged horizontal detailed sectional view taken as indicated by line 6-6 on Fig. 2 showing one of the spring adjusting nuts. Fig. 7 is a face or front elevation of the device with the weights removed and the bars held in the extended horizontal positions. Fig. 8 is a top or plan view of the device with the bars held in the elevated plane and provided with the spring means for yieldingly resisting outward swinging of the bars. Fig. 9 is an enlarged vertical detailed sectional view taken as indicated by line 9-9 on Fig. 8. Fig. 10 is a perspective view of the clip for holding the bars in the elevated plane. Fig. 11 is an enlarged vertical detailed sectional view taken as indicated by line 11-11 on Fig. 8 and Fig. 12 is an enlarged fragmentary side elevation of one of the bar levers.

The exercising device of this invention may be said to comprise, generally, a mounting plate 10, a body 11 removably engaged on the plate 10, a pair of bars 12, means 13 for supporting the bars 12 on the body 11 for independent universal swinging and for rotation on their longitudinal axes, means 14 for yieldingly resisting swinging of the bars 12, and other elements, the details and functions of which will be later described in detail.

The mounting plate 10 is adapted to be applied to a wall W or other vertical support and serves to removably mount or carry the body 11. The plate 10 presents an extensive flat rear face for bearing on the wall W and has spaced openings near its edges for receiving screws 15, bolts or similar members for attaching the plate to the wall W. Spaced downwardly convergent ribs 16 are provided on the front of the plate 10 and these ribs 16 carry inturned flanges 17. The ribs 16 and their flanges 17 define a socket or pocket 18 for receiving a part of the body 11, as will be later described. The ribs 16 may terminate before reaching the lower end of the plate 10 and their lower ends may be spaced apart. It will be observed that the plate 10 is an inexpensive one-piece element easily installed on the wall W or other selected support. Where the exercising device is to be used by persons of different heights it may be desired to provide a series of vertically spaced plates 10 or to arrange the plates 10 in other manners at different elevations as required.

The body 11 serves to carry the bars 12 and other elements of the device and is removably seated on the plate 10. In the preferred structure the body 11 is a rigid one-piece member including a substantially vertical base or rear part 19 designed to fit the pocket 18. The part 19 has downwardly convergent side edges and is proportioned to engage behind the flanges 17 of the ribs 16. The body part 19 is merely passed downwardly into the pocket 18 from its upper end and the tapered edges of the part 19 seat down on the inner sides of the convergent ribs 16 to dependably support the body 11. The lower end of the body part 19 is exposed below the ribs 17 so that it is readily accessible in the event the part 19 sticks in the pocket 18. The broad rear side of the part 19 flatly bears against the face of the plate 10 and the engagement of the edge portions of the part 19 with the ribs 16 and their flanges 17 dependably retains the body 11 in the operative position. The body 11 further includes a forwardly projecting generally horizontal major part 20. The body part 20 projects forwardly from the upper end of the rear part 19 and is provided at its under side with a strengthening rib 21 which merges with the back part 19. Lat-

erally projecting lugs 22 are provided on the part 20 adjacent its outer end. The lugs 22 are aligned and present flat parallel front and rear ends and cylindrically curved side surfaces. The body 11, just described, may be a simple one-piece casting.

The bars 12 are elongate members forming the principal operating elements of the device, being adapted to be swung or manipulated by the user. There is a pair of like or complementary bars 12 formed at their inner ends for connection with the mounting means 13 and provided at their outer ends with handles or grip means. The bars 12 are preferably formed of tubular stock such as pipe or tubing. Threaded stems 23 are fixed to the inner ends of the bars to continue inwardly therefrom. The stems 23 may be fitted in the tubular stock of the bars 12 and then welded or otherwise fixed to the bars or the inner end portions of the bars themselves might be threaded. The handles on the outer ends of the bars 12 may be of any suitable construction or form. In the embodiment of the invention illustrated, the handles include stirrup like handle members 24 fixed to the ends of the bars 12 as by welding. The members 24 extend laterally from the bars 12 and then curve forwardly. Suitable grips 25 are secured to the outer ends of the members 24 to extend at right angles therefrom. The grips 25 are spaced beyond the outer ends of the bars 12 and are preferably arranged so that their longitudinal axes intersect the longitudinal axes of the bars. The grips 25 may be formed of or may carry rubber, wood, or the like, for safe convenient engagement by the user. As illustrated in the drawings, the major tubular portions of the bars 12 are preferably uniform in external diameter.

The means 13 mount or support the bars 12 on the outer portion of the body 11 for universal swinging and for free independent rotation about their respective longitudinal axes. The means 13 each includes a mounting member which I will term a carrier 26. Each carrier 26 has a pair of spaced generally parallel vertical yokes or forks 27 and a pair of spaced generally parallel yokes or forks 28 projecting forwardly from the front side of the foremost fork 27. The forks 28 are disposed at right angles to the forks 27. The forks 27 receive or straddle a lug 22 so the inner and outer forks 27 are at the opposite ends of the lugs.

The invention provides novel means for pivotally connecting the forks 27 of the carriers 26 with the lugs 22 to allow the carriers 26 and their bars 12 to move about generally horizontal axes. The lugs 22 have central horizontal openings 29 and the forks 27 have openings 30 for registering with the openings 29, see Fig. 4. Pivot pins 31 are passed rearwardly into the openings 29 and 30. The shafts 31 are of sufficient length to extend rearwardly beyond the rear sides of the rear forks 27 and cotter keys 32 are passed through transverse openings in the pins 31 at the rear sides of the rear forks 27 to prevent forward displacement of the pins 31. Raised parts or projections 33 are provided on the carriers 26 behind the ends of the pins 31 to hold the pins against rearward displacement. With the structure just described the carriers 26 and their respective bars 12 are mounted on the body 11 to swing about horizontal axes normal to the wall W and spaced at opposite sides of the body 11.

The means 13 further include structures for

connecting the bars 12 with their carriers 26 for swinging about axes normal to the axes of the pins 31 and for rotation about their longitudinal axes. The forward forks 28 of the carriers 26 have transverse openings 34 normal to the longitudinal axes of the adjacent pins 31. The axes of the openings 34 may intersect the axes of the pins 31. Pins 35 of substantial diameter are pivotally carried in the openings 34 to extend between the forks 28. Transverse openings 36 are provided in the pins 35 intermediate their ends. The axes of the openings 36 may occupy the same planes as the longitudinal axes of the horizontal pivot pins 31. The threaded stems 23 of the bars 12 have reduced or plain end parts 37 which pass through and freely turn in the openings 36. The reduced parts 37 leave shoulders 38 on the stems 23 which cooperate with the pins 35 to limit endwise movement of the bars 12 in one direction. Washers 39 are provided on the reduced end parts 37 and cotter keys 40 are passed through transverse openings in the parts 37 behind the washers so that the washers cooperate with the pins 35 to hold the bars against longitudinal movement in the other direction. The washers 39 are engageable with the forks 28 to prevent displacement of the pins 35 from the openings 34. With the structure just described the bars 12 are independently swingable about axes transverse of the axes of the pins 31, giving the bars complete or universal swinging motion. It will be observed that while the bars 12 are freely rotatable about their individual longitudinal axes they are effectively held against longitudinal movement and displacement.

The means 14 yieldingly resists inward swinging of the bars 12, that is, swinging of the bars toward one another, when they are arranged as shown in Figs. 7 and 8. It is a feature of the invention that the means 14 are independently adjustable to vary the resistance to swinging of their respective bars. Each means 14 includes a nut 41 having threaded engagement with the threaded stem 23 of the bar 12. The nuts 41 are adapted to travel along the stems 23 upon rotation of the bars 12, as will be later described. Each nut 41 has a pair of diametrically opposite radial arms 42.

The means 14 further includes rearward extensions or levers 44 on the carriers 26. The levers 44 may be integral continuations of the carriers and in the preferred construction extend rearwardly toward the wall W and then curve laterally. As best illustrated in Fig. 12 of the drawings, the rear or outer ends of the levers 44 are forked or divided so each has two branches 45. The arms 42 of the nuts 41 and the outer ends of the branches 45 of the levers 44 have eyes or openings 46.

The means 14 for yieldingly resisting inward swinging of the bars 12 further include sets or pairs of extensible springs 47. The springs 47 have hooked or looped end parts engaged in the openings 46 whereby the springs are coupled between the arms 42 of the nuts 41 and the branches 45 of the levers 44. The springs 47 may be coiled springs of selected or required length and strength. The length of the arms 42 and the spacing of the branches 45 are sufficient to cause the springs 47 to clear the carriers 26, the lugs 22, etc. when the bars 12 are swung toward one another in elevated positions such as shown in Fig. 8 of the drawings. This prevents the springs 47 from contacting the carriers 26 and other

parts when the bars 12 are operated in this way with the nuts 41 adjusted inwardly toward the carriers 26. It will be apparent that the invention can be carried out by using a single spring for each bar instead of pairs of springs as just described.

The coupling of the spaced springs 47 with the nut arms 42 effectively holds the nuts 41 against rotation. Accordingly, rotation of a bar 12 causes its respective nut 41 to travel in or out on the stem 23 depending upon the direction of rotation of the bar. This inward or outward adjustment of the nuts 41 regulates or changes the leverage of the means 14, that is, it varies the leverage of the springs with reference to the bars. It will be apparent how adjustment of the nuts 41 along their stems 23 regulates the action of the means 14. When the bars 12 are extended in a horizontal plane, as shown in Fig. 7 of the drawings, the grips 25 are grasped by the user and the bars are drawn inwardly or toward one another. This operation of the bars 12 is resisted by the springs 47, the springs being stretched or elongated upon inward swinging of the bars. The action or resistance offered by the springs 47 with a given swinging of the bars 12 depends upon the adjustment of the nuts 41 on the stems 23. Simple rotation of the individual bars 12 regulates the means 14 to condition the device for use by various individuals and the means 14 may be quickly and easily adjusted to provide any desired degree of resistance to inward swinging of the bars.

The invention provides a removable and readily adjustable means for increasing the weight of the bars to impose an additional load on the arms of the user. One or more weights 48 may be provided for each bar 12. The weights 48 are preferably formed of material of relatively high specific gravity, for example, they may be formed of cast iron, or the like. Each weight 48 may be in the form of a disc provided with a notch 49 extending from its periphery inward to its center and the inner parts of the notches 49 are rounded to receive or conform to the bodies of the bars 12, see Fig. 5. A lug 50 projects inwardly from one wall of each notch 49 and set screws 51 are threaded inwardly through openings in the lugs. When the set screws 51 are backed away the weights 48 are readily arranged on the bars 12. The weights 48 may be shifted longitudinally along the bars 12 to selected positions and the screws 51 tightened down to clamp the weights 48 in the selected places. It will be seen that by shifting the weights 48 inward or outward on the bars 12 that the leverage effect of the weights 48 on the user's arms may be reduced or increased at will. Furthermore, each bar 12 may be provided with one or more weights 48, as desired or required. The weights 48 may be readily removed when it is preferred to use the bars without weights.

It may be desired to provide the device with optional or removal means for holding the bars 12 in raised or elevated positions and in a common horizontal plane as shown in Fig. 7. This means comprises a simple clip 52 of inverted U shape. The clip 52 may be an elongate member provided at its opposite ends with down turned ears 53. With the bars 12 brought to raised positions in a common horizontal plane, as shown in Fig. 7, the clip is placed on the upper side of the body 11 to extend across the tops of the lugs 22 with the ears 53 extending downwardly at the outer sides of the lugs 22 to engage between the

lugs 22 and the inner sides or faces 54 of the carriers 26. Figs. 7, 8 and 9 of the drawings illustrate the manner in which the clip 52 extends across the upper face of the body 11 and has its ears 53 engaging between the lugs 22 and the inner surfaces 54 of the carriers 26. The engagement of the carrier surfaces 54 with the clip ears 53 prevents downward swinging of the carriers and thus retains the carriers 26 and their respective bars 12 in the raised common plane. When the clip 52 is employed the user is relieved of the weight of the bars 12, carriers 26, etc. and the arms may be operated horizontally without subjecting the user to the weight of these parts. The clip 52 may be left in place as long as required and may be easily disengaged and removed from the device when it is desired to allow the bars 12 to be used in the usual way and to normally hang down adjacent the wall W.

As illustrated in Figs. 8 and 11 of the drawings the device may embody means for yieldingly resisting outward swinging of the bars 12, that is, movement of the bars away from one another when in the raised operative position. This means for yieldingly resisting outward movement of the bars 12 is adjustable. The means for resisting outward swinging of the bars 12 includes clips or clamps 56 engageable with the bars 12. The clamps 56 are yoke like parts shaped to conform to the bodies of the bars 12 and provided with spaced out turned arms 57, see Fig. 11. The opposite sides of the clamps 56 have projecting lugs or ears 58. Clamp screws 59 are arranged in openings in the arms 57. Upon tightening of the screws 59 the arms 57 are drawn toward one another to tighten the clamps 56 on the bars 12. Upon loosening of the screws 59 the clamps 56 expand and are freely shiftable along the bars. An extensible coiled spring 60 has loops 61 at its ends engaged through openings in the lugs 58 of the clamps 56. The spring 60 is formed and proportioned to resist outward swinging of the bars 12 the desired extent and may be replaced by other springs 60 of different weights or strengths. When the spring 60 is to be employed the nuts 41 are preferably threaded inwardly to their innermost positions to reduce the movement resisting action of the springs 47 to a minimum. The spring 60 is of greater strength than the springs 47 when the springs 47 are thus retracted. The engagement of the hooks 61 with the lugs 58 may be such that the spring 60 may be detached from the clamps 56 to permit the employment of weaker or stronger springs or to permit the use of the device without a spring for resisting outward swinging of the bars 12. The clamps 56 may be constructed so that upon removal of their screws 59 they may be removed or disengaged from the bars 12. The clamps 56 may be slid inwardly on the bars to the reduced stems 23 and may be constructed to be readily disengaged from the stems. The clamps 56 may be replaced on the bars when it is desired to again use the spring 60.

In the operation of the device it will be assumed that the body 11 is removably seated on the plate 10 and that the device is to be employed without the clip 52, the weights 48 or the spring 60. The means 14 for yieldingly resisting inward swinging of the bars 12 may be independently adjusted to offer the required resistance to movement of the bars. As above described, these adjustments are made by merely rotating the bars 12 to thread their respective nuts 41 in or out on the stems 23. The resistance

to movement of the bars 12 may be equal or unequal resistances may be provided if desired.

In exercising with the device the user faces the apparatus and holds the grips 25 with the palms up. The bars 12 are then swung outwardly or apart until the user's arms are extended substantially straight out or horizontally from the sides of his body. The user assumes a good postural standing position with his arms extended and leans forward to shift a portion of his weight to the balls of his feet. This thrusts his body forward and applies a tension to the muscles of the chest and shoulders. While leaning forward the user may rock back and forth slightly to work the chest muscles and vary the tension on the same. This exercise is completed when the user returns his body to the original vertical position.

The device may be employed to actively work and shorten the muscles of the back in the region of the shoulders. The user assumes a position between the bars 12 with his arms extended horizontally and grasps the grips 25. The user then moves his body forward to bring his shoulders slightly ahead of the line extending between the grips 25. The bars 12 are then pulled or drawn toward the body, bending the elbows slightly. In performing this operation the resistance to movement of the bars 12 offered by the springs 47 should be overcome as far as possible by the muscles of the back instead of those of the arms. The arms are returned to the extended substantially horizontal positions and the exercise repeated. The exercises above described and various other exercises may be performed with the user either standing or sitting as conditions may require. A wide variety of exercises may be carried out by using the bars 12 when extended at different angles and by varying the adjustment of the spring means 14.

It will be apparent that a wide variety of additional exercises can be had by adding the weights or by adding the spring 60, or both.

Having described only typical preferred forms and applications of my invention, I do not wish to be limited or restricted to the specific details herein set forth, but wish to reserve to myself any variations or modifications that may appear to those skilled in the art or fall within the scope of the following claims.

Having described my invention, I claim:

1. An exercising device comprising a body, a pair of bars, means for mounting the bars on the body for swinging movement toward and away from one another and for rotation about their longitudinal axes, and means for yieldingly resisting swinging of the bars in one direction comprising a spring for each bar anchored at one end, and a member movable along the bar upon rotation of the bar about its longitudinal axis and securing the other end of the spring.

2. In an exercising device, a bar, means mounting the bar for swinging movement and for rotation about its longitudinal axis, and means for yieldingly resisting swinging of the bar in one direction, comprising a nut threaded on the bar to travel therealong, and a spring having one end anchored and having its other end secured to the nut to prevent rotation of the same and to be adjusted upon rotation of the bar.

3. An exercising device comprising a body, a pair of bars, means for mounting corresponding ends of the bars on the body for swinging movement about generally vertical axes so that the

user may swing the bars toward and away from one another, handle on the bars, a spring for extending between the bars to yieldingly resist swinging of the bars away from one another about said axes, and means for connecting the spring with the bars and shiftable along the bars to vary the action of the spring.

4. An exercising device comprising a body to be mounted on a vertical support, carriers secured to the body for independent swinging about spaced horizontal axes, bars carried by the carriers for swinging about axes transverse of the first named axes and adapted to be swung toward and away from one another in a horizontal plane, and releasable means for preventing swinging of the carriers to retain the same in positions where the bars are swingable about substantially vertical axes to move in a substantially horizontal plane.

5. An exercising device comprising a body to be mounted on a vertical support, carriers in front of the body, lugs on opposite sides of the body, forks on the carriers receiving the lugs, substantially horizontal pins carried by the lugs and cooperating with the forks to swingably mount the carriers on the body, forks on the front sides of the first named forks, bars to be swung by the user and arranged with their inner ends in the second named forks, and pins carried by the second named forks and having transverse openings receiving the bars to support the bars for swinging about axes transverse of the axes of movement of the carriers.

6. An exercising device comprising a body to be mounted on a vertical support, carriers in front of the body, lugs on opposite sides of the body, forks on the carriers receiving the lugs, substantially horizontal pins carried by the lugs and cooperating with the forks to swingably mount the carriers on the body, forks on the front sides of the first named forks, bars to be swung by the user and arranged with their inner ends in the second named forks, pins carried by the second named forks to pivot about axes transverse of the axes of movement of the carriers, the last named pins having transverse openings, and means retaining the inner portions of the bars in said transverse openings for rotation.

7. An exercising device comprising a body to be mounted on a vertical support, carriers in front of the body, lugs on opposite sides of the body, forks on the carriers receiving the lugs, substantially horizontal pins carried by the lugs and cooperating with the forks to swingably mount the carriers on the body, forks on the front sides of the first named forks, bars to be swung by the user and arranged with their inner ends in the second named forks, pins carried by the second named forks to pivot about axes transverse of the axes of movement of the carriers, the last named pins having transverse openings, means retaining the inner portions of the bars in said transverse openings for rotation, and means for yieldingly resisting swinging of the bars regulable by rotation of the bars.

8. An exercising device comprising a body to be mounted on a vertical support, carriers in front of the body, lugs on opposite sides of the body, forks on the carriers receiving the lugs, substantially horizontal pins carried by the lugs and cooperating with the forks to swingably mount the carriers on the body, forks on the front sides of the first named forks, bars to be swung by the user and arranged with their inner ends in the second named forks, pins carried by the second

5 named forks to pivot about axes transverse of the axes of movement of the carriers, the last named pins having transverse openings, means retaining the inner portions of the bars in said transverse openings for rotation, and means for each bar for yieldingly resisting swinging of the same regulable by rotation of their respective bars.

9. An exercising device comprising a body to be mounted on a vertical support, carriers supported on the body to swing about horizontal axes, levers on the carriers projecting inwardly toward the support, bars secured to the carriers to swing about axes transverse of the axes of movement of the carriers so that they may be swung toward and away from one another by the user, and springs coupled between the bars and levers to yieldingly resist swinging of the bars toward one another.

10. An exercising device comprising a body to be mounted on a vertical support, carriers supported on the body to swing about horizontal axes, levers extending inwardly from the carriers toward the support, bars secured to the carriers to swing about axes transverse of the axes of movement of the carriers so that they may be swung toward and away from one another by the user, parts adjustable along the bars, and springs coupled between the levers and said parts for yieldingly resisting swinging of the bars toward one another.

11. In an exercising device, a mounting means, a pair of bars, and means for supporting the bars on the mounting means comprising carriers supported on the mounting means for movement about spaced horizontal axes, and means for supporting the bars on the carriers for movement about axes substantially intersecting the axes of movement of the carriers.

12. In an exercising device, a mounting means, 40 a pair of bars, a carrier for each bar, means for supporting the carriers on the mounting means for movement about substantially horizontal axes, and means in adjacent relation to the last named means for supporting the inner ends of the bars 45 on the carriers for movement about axes substantially intersecting the axes of movement of the carriers.

13. An exercising device comprising a body to be mounted on a vertical support, a pair of exercising bars, a carrier for each bar, means for supporting the carriers on the body for movement about substantially horizontal axes, means for supporting the bars on their respective carriers for swinging movement about axes which are 55 in substantially intersecting relation to the axes of movement of the carriers, levers on the carriers extending inwardly toward the support, and means for yieldingly resisting swinging of the bars in one direction comprising springs connected with the bars and anchored to said levers.

14. An exercising device comprising a body to be mounted on a vertical support, a pair of exercising bars, a carrier for each bar, means for supporting the carriers on the body for movement about substantially horizontal axes, means for supporting the bars on their respective carriers for swinging movement about axes which are in substantially intersecting relation to the axes of movement of the carriers, levers on the 65 carriers extending inwardly toward the support, and means for yieldingly resisting swinging of the bars in one direction comprising nuts adjustably screw threaded on the bars, and springs connected between the nuts and the levers.

75 WILLIAM H. MAXWELL.
